ABSTRACT

We disclose methods and means for drying a compressed working fluid in which a branch current of hot unsaturated working fluid is conducted directly from the compressor to the regeneration zone of a sorption-drying apparatus comprising a rotatable drying element driven by a motor. We also disclose means controlled by the unloading device of the compressor for disconnecting the driving of the drying element when the compressor unloads.

METHOD AND DEVICE FOR DRYING A COMPRESSED WORKING FLUID

BACKGROUND OF THE INVENTION

The present invention concerns a method and a device for drying a compressed working fluid such as air or some other gas compressed in a compressor. It is known to use so-called sorption-drying apparatus for drying air or other gases, whereby such apparatuses are referred to that comprise a vessel including a water-adsorbent, such as silica gel, lithium chloride or other like substances or water-absorbing material, such as asbestos sheathing, porous bodies or the like or a combination of both. It is also known to include a rotatable drying element in such drying apparatus in which the working fluid passes through a drying zone and in which a regeneration zone is arranged, which is passed by a working fluid for regeneration of the drying element. A known drying element of this type consists of pleated asbestos sheathing, which has been impregnated with lithium chloride and possibly been armoured to resist the mechanical strains and which forms a rotor with a great number of axial channels, which rotor is arranged in a housing which includes separate conduits for the working fluid which is to be dried and for the fluid used for the regeneration. Drying plants of the above mentioned type for drying air of atmospheric pressure do not offer any great problem. But as soon as drying of compressed air or some other compressed gas is concerned, a great deal of problems arise which are closely allied to the special properties and operating conditions of compressed air or compressed gas in a compressor plant. A drawback with known drying plants for compressed air or compressed gas is that they include relatively expensive heat exchangers. Another drawback is that they are sensitive to different loadings of the compressor. In known sorption-drying apparatuses comprising a rotatable drying element, the drying element is continuously driven by a motor. When the compressor runs unloaded, there is no fluid supplied to the regeneration zone of the drying apparatus for regeneration of the drying element. As a consequence a wet part of the drying element may pass the regeneration zone when the compressor runs unloaded and thus enter the drying zone in a wet condition. This will of course spoil the drying result. The invention is aiming to bring about a method and devices for drying a compressed working fluid by using a minimum of heat exchangers and by which the operating conditions of the compressor will not prejudice the drying result or the drying apparatus. The invention is mainly characterized by those methods and devices that are stated in the below given claims.

BRIEF DESCRIPTION OF THE DRAWINGS

The method according to the invention is more closely described below in conjunction with two schematic diagrams.

FIG. 1 shows one embodiment of the invention. FIG. 2 shows another embodiment of the invention.

SUMMARY OF THE INVENTION

The diagrams show examples of devices for carrying out the method in two different modifications. In a broad sense the method according to the invention is based upon the novel concept that a compressed working fluid compressed in a compressor is dried by con-

ducting a main current of the working fluid from the compressor through an after-cooler including a water separator and after that through a drying zone in a regenerative sorption-drying apparatus, and by conducting a branch current of hot unsaturated working fluid from the compressor through a regeneration zone in the drying apparatus and thereafter via an after-cooler including a water separator together with the main current through the drying zone to a delivery conduit. The 5 method according to the invention is based on the observation that the hot working fluid, which is delivered by the compressor, has such a high temperature and such a low relative moisture proportion that a branch current can be separated and used for regeneration by 10 conducting it through a regeneration zone in the drying apparatus for carrying away the moisture which has been transferred to the regeneration zone from other parts of the drying apparatus, where it has earlier been taken up, through the rotation of the drying element. 15 The main current of the working fluid is conducted from the compressor through an after-cooler including a water separator and after that to the drying zone of the sorption-drying apparatus. The branch current used for regeneration is suitably conducted via a cooler including a water separator from the regeneration zone to the main current and together with this through the drying zone. The method is suitably carried out so that the pressure in the regeneration zone always is kept somewhat lower than the pressure in the drying zone in 20 order to permit a possible leakage of working fluid to pass from the dry part to the regeneration zone.

DESCRIPTION OF A SPECIFIC EMBODIMENT

In the diagram shown in FIG. 1 a compressor of arbitrary kind, for instance a two-stage piston compressor or a screw compressor is indicated by 1, 33, which is driven by a motor 34 and supplied with working fluid, for instance air, via an intake filter 2 and a conduit 3. The compressor may include an intermediate cooler as 35 indicated at 35. From the compressor the hot compressed air flows through a conduit 4, 5 to an after-cooler 6 including a water separator from which the air flows as a main air current through a conduit 7 and an ejector 8 to a sorption-drying apparatus 9. The sorption-drying apparatus 9 includes a rotor 10, which forms a drying element that in a known manner may consist of pleated asbestos sheathing which has been impregnated with lithium chloride and reinforced in a suitable manner with a metal wire armament or the like 40 to resist the mechanical strains during different moisture conditions. The rotor 10 is made in such a way that the working fluid is able to flow axially through the rotor through a great number of relatively thin channels. A sector of the rotor is at its ends axially shielded 45 with shields 11, 12 so that a regeneration zone 13 is formed in the rotor, which during the rotation of the rotor goes round the rotor in succession. The rest of the rotor forms a drying zone 14. Instead of letting the rest of the rotor form a drying zone, a cooling zone may be 50 formed between the regeneration zone 13 and the drying zone 14. This has for its purpose to cool the rotor material before it enters the drying zone. The cooling may for instance be accomplished with dry gas or wet gas, which after having passed the cooling zone is conducted back to the main current in the same manner as the regeneration gas or together with it. There is no 55 cooling zone shown in the drawings. The rotor is driven 60 by the motor 34. The apparatus 9 is connected to a delivery conduit 15.

by a motor 15 which, when the compressor is electrically driven, is suitably constituted by an electro-motor including a suitable gearing for reducing the number of revolutions to that at which the rotor rotates. The motor is supplied with current from an electric line 16 via a switch 17, which is suitably manoeuvred with compressed air in connection with the unloading device 18 of the compressor via a manoeuvring-cylinder 19 which closes the switch 17 when the compressor is loaded.

The compressed air or compressed gas dried in the drying zone 14 is conducted to suitable consumers through a pressure conduit 20 for dry air or gas. For the regeneration of the sorption-drying apparatus, a branch conduit 21 is branched from the conduit 4, 5. The conduit 21 includes a restriction 22 constituted by a throttle-disc or an adjustable throttle-valve. A branch current of the working fluid is conducted directly from the pressure side of compressor through the conduit 21 to the regeneration zone 13 in the drying apparatus. This branch current has in a compressor plant for a pressure of for instance 7 atmospheres above the atmospheric pressure, a temperature of more than 100 centigrades and at this temperature a low relative moisture proportion (for instance 20-30 percent) and can, therefore, partly heat the rotor material in the regeneration zone and partly carry away the moisture therefrom. From the regeneration zone the branch current flows through the conduit 23 to a cooler 24 including a water separator and therefrom through a conduit 25 to the suction-side of the ejector 8. The branch current is drawn into the main current by the ejector 8 and moves on together with the latter current into the drying zone 14 of the drying apparatus. The after-cooler 6 includes a cooling element 26, which is fed with cooling-water through a conduit 27 and the cooler 24 includes a cooling element 28, which is fed with cooling-water from a conduit 29. 30 and 31 are condensed-water separators of conventional kind included in the coolers.

The restriction 22 and the ejector 8 are so chosen and dimensioned that a somewhat lower pressure is obtained in the regeneration zone 13 than in the drying zone 14. By reason thereof any possible leakage from one zone to another will be constituted by dried air or dried working fluid flowing into the regeneration zone.

Upon occurrence of a possible decrease in the loading of the compressor, the plant according to FIG. 1 will still work substantially as when fully loaded. When the compressor is unloaded the main current through the cooler 6 and the conduit 7 is, however, interrupted and consequently no branch current can pass through the regeneration zone. The device is, therefore, so made that the unloading device of the compressor upon unloading of the compressor, simultaneously disconnects the motor 15 which normally drives the drying element 10. Thereby a more reliable function of the drying apparatus is obtained, and the drying result will not be affected.

In the modification according to FIG. 2 the cooler 24 for the branch air current or branch gas current is eliminated and an ejector 32 has been arranged in the conduit 5 leading to the after-cooler 6 instead of the ejector 8 in conduit 7. The rest of the plant according to FIG. 2 is made in the same manner as the plant according to FIG. 1 and equivalent details have, therefore, been indicated with the same reference numerals as in

FIG. 1 and will not be described again. The working fluid current used for regeneration is in the modification according to FIG. 2 supplied through the conduit 23, 25 to the suction side of the ejector 32 and passes together with the main air current through the after-cooler 6. The pressures indicated in FIG. 1 are related in the following way: P is higher than P_1 , which is higher than P_2 and higher than P_3 , which is the pressure in the regeneration zone. Like conditions must of course prevail in the plant according to FIG. 2 in which, however, the ejector 32 has to overcome a larger pressure decrease than the ejector 8 in the plant according to FIG. 1. The cooler 6 in FIG. 2 will also become bigger than in FIG. 1.

The above described methods and devices are only to be regarded as examples which may be modified in different ways within the scope of the claims. The ejectors may for instance be substituted by ordinary pumps. In electrically driven compressor plants electrical supervision devices for unloading may be used to supervise the motor 15 electrically and disconnect it when unloading. A pneumatically or hydraulically supervised pressure fluid motor may be arranged instead of 15. The coolers 6, 24 may be air-cooled and the water separators 30, 31 may be introduced separate from the coolers. The drying apparatus may consist of a number of drying towers or the like.

What we claim is:

1. The method of drying hot working fluid from a compressor comprising:
  - a. passing a main current of hot compressed working fluid in a main passage through an after-cooler to remove heat therefrom;
  - b. passing said cooled current through a drying zone in a regenerative sorption-drying apparatus;
  - c. passing a branch current of hot unsaturated working fluid from said compressor through a regeneration zone of said sorption-drying apparatus;
  - d. merging said currents after having been passed through said regenerative sorption-drying apparatus, and
  - e. passing said dried and merged currents to a common discharge outlet.
2. A method according to claim 1, at which the branch current is restricted so that the pressure in the regeneration zone is lower than in the drying zone.
3. A method according to claim 1, at which the branch current is cooled together with the main current in the after-cooler which includes a water separator.
4. A method according to claim 1, at which a rotatable drying element of the sorption-drying apparatus is alternatively passed through the drying zone and the regeneration zone in succession.
5. A device for drying a compressed working fluid comprising a compressor, an after-cooler including a water separator, a sorption-drying apparatus comprising a drying zone and a regeneration zone, a conduit for conducting hot working fluid from the compressor to the after-cooler, a conduit for conducting the cooled working fluid from the after-cooler to the drying zone, a branch conduit for conducting hot working fluid from the compressor to the regeneration zone for supplying hot unsaturated working fluid to the regeneration zone and a conduit for conducting working fluid from the regeneration zone via a cooler to the drying zone.

6. A device according to claim 5 comprising a restriction in the branch conduit between the compressor and the regeneration zone.

7. A device according to claim 5 in which an ejector is arranged in the conduit from the after-cooler to the drying zone and the conduit from the regeneration zone to the drying zone is connected to the suction side of the ejector.

8. A device according to claim 5 in which an ejector is arranged in the conduit from the compressor to the after-cooler and the conduit from the regeneration zone to the drying zone is connected to the suction side of the ejector.

9. A device according to claim 7 in which the restriction, the ejector and the flow resistances in the after-cooler, the regeneration zone and the conduits are so dimensioned that the pressure in the regeneration zone is somewhat lower than the pressure in the drying zone when the compressor is working loaded.

10. A device according to claim 8 in which the restriction, the ejector and the flow resistances in the after-cooler, the regeneration zone and the conduits are so dimensioned that the pressure in the regeneration zone is somewhat lower than the pressure in the drying zone when the compressor is working loaded.

11. A device according to claim 5 in which the sorption-drying apparatus comprises a motor driven rotatable element, an unloading device in the compressor

and means controlled by the unloading device for disengaging said rotatable element upon unloading of the compressor.

12. A device for drying a compressed working fluid comprising a compressor, a regenerative sorption-drying apparatus comprising a rotatable drying element which is driven by a motor, an unloading device on the compressor and means controlled by the unloading device for disconnecting the driving of the drying element when the compressor unloads.

13. The method of drying hot working fluid from a compressor comprising:

- a. passing a main current of hot compressed working fluid in a main passage through an after-cooler to remove heat therefrom;
- b. passing a branch current of hot unsaturated working fluid from said compressor through a regeneration zone in regenerative sorption-drying apparatus;
- c. merging said branch current after having passed through said regeneration zone with said main current;
- d. passing said merged currents through a drying zone in said regenerative sorption-drying apparatus, and
- e. passing the thus dried and merged currents to a discharge outlet.
